UNITED STATES PATENT OFFICE.

WILLIAM AYRES, OF MOUNT HAMILTON, ONTARIO, CANADA, ASSIGNEE TO AMERICAN CAN COMPANY, OF NEW YORK, N. Y., A CORPORATION OF NEW JERSEY.

CAN END.

1,136,993.

Specification of Letters Patent. Patented Apr. 27, 1915.

Application filed July 29, 1912. Serial No. 711,967.

To all whom it may concern:

Be it known that I, WILLIAM AYRES, a citizen of Canada, residing in Mount Hamilton, in the Province of Ontario and Dominion of Canada, have invented a new and useful Improvement in Can Ends, of which the following is a specification.

This invention relates to improvements in sheet metal can ends more especially adapted for use in cans or vessels having paper or fiber sides or walls, and the invention consists in providing the sheet metal, countersunk can end with means for preventing a stack of the can ends from nesting together, and which same means, when the end is clamped on the yielding can body, will prevent the end from turning upon the body.

In the drawing which forms a part of this specification, Figure 1 is a vertical section of a can employing the improved ends. Fig. 2 is a horizontal section of the can end and can body on the line 2—2 of Fig. 1. Fig. 3 is a plan view of the improved can end, the same being shown as in a can end stack, and Fig. 4 is a vertical, sectional view of such a stack of can ends as is represented in Fig. 3.

In securing or crimping sheet metal can ends to paper bodies, it is usual and thought to be the best practice to form the can end with a countersunk portion snugly fitting inside of the paper body, and with a horizontal flange extending slightly beyond the outside of said body. In securing such an end to the body, it is better practice to curl this flange all around into strong contact with the paper wall, making a tight joint. This joint has the single defect, however, that the can end, being circular, can be turned upon the body, as, for example, in opening a screw nozzle or in handling the can, and, especially where screw caps or nozzles are employed in the outfit or vessel, such slight freedom to turn is a marked disadvantage and may result in the creation of leaks or loosening of the joint. Another difficulty encountered in the manufacture of cans of this character, is the liability of the can ends, when stacked up in a pile, to nest together, rendering the operation of feeding the can ends difficult.

In the present invention, I propose to overcome all of these difficulties by the sim-

ple expedient of interrupting the circular contour of the countersunk portion of the can end by a bulge or bulges, increasing at these points the diameter of the internally fitting countersunk portion of the can end. When the can ends so constructed are stacked up, the chance of their nesting together, (which could only take place if the bulges of one can coincide with those of the adjacent one), are so small as to be negligible. And when such a can end is crimped upon the yielding paper body, these bulges cause a small distortion of the body out of a true circle, so that the can end cannot be turned upon the body after the joint is formed.

In the accompanying drawing, A is a sheet metal can end having the vertical countersunk wall *a* and made with the horizontally extending flange *a*¹ adapted to be curled inwardly against the paper can body B by any suitable crimping die or roller machine such as are well known in the art. The vertical wall *a* is made with bulges *c* which are not great enough in extent to interfere with the insertion of the countersunk portion of the can end into the body. After the can end and body are brought together, the flange is crimped inwardly into contact with the yielding substance of the body, and these bulges *c* cause a harder gripping action between the end of the body at that point, which renders it impossible to subsequently turn the end upon the body. At Figs. 3 and 4, a stack of the can ends is shown as though in the stack guides D to illustrate the nesting preventive action of the bulges when the can ends are stacked. This simple expedient adds practically nothing to the cost of the can end in its manufacture and yet accomplishes, as above stated, several valuable results.

I claim:

1. A can end having a laterally extending flange and a countersunk central portion, the vertical wall of the countersunk portion being formed with outwardly bulged portions extending upwardly and downwardly along the said vertical walls, whereby the nesting of the can end is prevented when it is stacked with others of a similar structure, substantially as specified.

2. A sheet metal can end having a laterally extending circumferential and coun-

tersunk central portion, the vertical wall of the countersunk portion being formed with outward bulges at three circumferential equally spaced points, the said bulges extending upwardly and downwardly along the said vertical wall, the bulges preventing the can end from nesting with others of a similar structure when stacked, substantially as specified.

WILLIAM AYRES.
